WINDOW LOCK

Tolbert Hannon, San Francisco, Calif.

Application April 23, 1945, Serial No. 589,731

4 Claims. (Cl. 292—264)

My invention relates to window locking means, and particularly to a device operable to lock or to limit opening movement of one or both of a pair of movable window sashes.

It is among the objects of my invention to provide a window lock by which a window sash may be locked in closed position, and which may be readily adjusted to permit limited opening movement of the window while locking it against opening movement beyond a predetermined position.

Another object is to provide means for shielding and supporting a flexible locking chain across the meeting edges of relatively movable window sashes to prevent tampering with the chain from outside the window, and to prevent interference with the movement of the sashes within the range of permitted movement.

My invention possesses other objects and features of value, some of which with the foregoing will be set forth in the following description of the invention. It is to be understood that I do not limit myself to the showing made by the said description and the drawing as I may adopt variant forms of the invention within the scope of the appended claims.

In the drawing:

Figure 1 is a vertical section through the meeting rails of a pair of window sashes, the locking device of my invention being applied thereto and shown in side elevation.

Figure 2 is an inside front elevation of the locking device and portions of the window sashes of Figure 1, drawn upon a smaller scale, and shown in partially open position.

In terms of broad inclusion, the window locking device of my invention comprises a chain secured at one end to an upper sash and adjustably engageable with chain engaging means upon the companion lower sash. A guard is provided for shielding and supporting the chain between its points of attachment to the sashes; and means is provided for stacking slack portions of the chain to prevent interference thereby with the movement of the sashes to their closed positions.

In terms of greater detail, the window lock of my invention comprises a chain 1 secured to a chain mounting plate 2 attachable to the lower rail 3 of a movable window sash 4, as for example the upper sash of a pair of relatively movable window sashes, by screws or other suitable securing means 5. The chain 1 is preferably linked to an upturned lug 6 projecting angularly from the plate 2 adjacent one end thereof.

A chain engaging hook 7 is mountable upon a 55 prowler to gain access to the room.

member 8 with respect to which the sash rail 3 is movable. As illustrated in the drawing, the member 8 is the upper rail of a window sash 9 associated with the sash 4 as the lower sash of a pair. A fixed sill may be utilized for mounting the hook 7 if desired. Preferably the hook 7 is provided with a base 10 arranged to seat against the rail 8 and to be secured thereto by suitable screws or other securing means. The body of the hook is preferably disposed in a substantially horizontal plane, and may advantageously be provided with an offset portion 11 forming a detent whereby the chain may be held taut after being moved onto the hook from the side.

15 A guard 12 carried by a base plate 13 is arranged to be secured to the top of the rail 7, as by screws 14. A shield portion 15, preferably of trough-shaped cross-section, extends transversely across the meeting edges of the rails 3 and 8 and overhanging the chain mounting plate 2. The shield portion 15 only slightly clears a flange 16 which extends upwardly along the edge of the plate 2 adjacent the meeting edges of the sash rails. The shield 15 is substantially aligned with the hook 7, while the lug 6 to which the chain 1 is secured is laterally offset therefrom, as shown in Figure 2.

20 For locking the sashes 4 and 9 in their closed positions, the chain 1 is extended from the plate 2 through the shield 15 to the hook 7. The chain is drawn taut, and the nearest link is moved onto the hook 7. By moving the engaged link of the chain past the detent 11, the chain is effectively tightened and retained in locking engagement 25 with the hook. So placed, the chain effectually locks both sashes against movement relative to each other. In Figure 1, the chain 1 is shown in engagement with the hook 7, but not yet moved past the detent 11 for locking the sashes in closed position.

30 When it is desired to lock the sashes in a partially open position, the chain 1 is moved into engagement with the hook 7 at a selected point along the length of the chain such as to allow an amount of slack in the chain sufficient to permit the desired degree of relative movement of the sashes to an open position as shown in Figure 2. So fastened, the chain permits either sash to be moved until the slack in the chain is taken up, and then locks the sash against further movement. This permits the window to be opened at top or bottom, or both top and bottom, sufficiently to afford desired ventilation while locking the sashes against movement sufficient to permit a 35 prowler to gain access to the room.

The guard 12 with its shield extension 15 guides the chain from the plate 2 to the hook 7; and, at the same time, shields the chain against tampering by persons seeking to displace or sever the chain from outside the window. The flange 16, over which the shield 15 extends, aids in protecting the chain 1; and also serves to retain the chain upon the top of the rail 3, and out of the space between the rails 3 and 8 as the sashes are moved from a partially open to a closed position. This retention of the chain is materially aided by positioning the chain attaching lug 6 in offset relation. Thus, assuming the sashes are to be closed from a partially open position as shown in Figure 2, the chain lays itself in successive short loops back and forth behind the flange 16 until the sashes reach the desired relation and the slack is taken up. The successive loops are stacked in back of the flange 16, thereby preventing the chain from being caught between the approaching rails 3 and 8 and preventing complete closure.

I claim:

1. A lock for relatively movable upper and lower sashes comprising a chain mounting plate for the lower rail of the upper sash, a hook for the upper rail of the lower sash, a chain secured at one end to the plate and adjustably engageable with the hook at a selected point along the chain for limiting relative movement of the sashes, and a chain guard mountable upon the lower sash and overhanging the chain mounting plate for supporting and shielding the chain between the plate and the hook.

2. A lock for relatively movable upper and lower sashes comprising a chain mounting plate for the lower rail of the upper sash, a hook for the upper rail of the lower sash, a chain secured at one end to the plate and adjustably engageable

with the hook at a selected point along the chain for limiting relative movement of the sashes, a flange upwardly extending along the edge of the plate adjacent the meeting edges of the sashes, and a chain guard mountable upon the lower sash and overhanging the chain mounting plate for supporting and shielding the chain between the plate and the hook.

3. A lock for relatively movable upper and lower sashes comprising a chain mounting plate for the lower rail of the upper sash, a hook for the upper rail of the lower sash, a chain secured at one end to the plate and adjustably engageable with the hook at a selected point along the

chain for limiting relative movement of the sashes, the chain being secured to the plate at a point laterally offset from the point of engagement of the chain to the hook, a flange upwardly extending along the plate between the point of attachment of the chain thereto and the hook, and a chain guard mountable upon the lower sash and overhanging the chain mounting plate for supporting and shielding the chain between the plate and the hook.

4. A lock for relatively movable upper and lower sashes comprising a chain mounting plate for the lower rail of the upper sash, a hook for the upper rail of the lower sash, said hook having an offset portion for resisting displacement of the

chain therefrom, a chain secured at one end to the plate and adjustably engageable with the hook at a selected point along the chain for limiting relative movement of the sashes, and a chain guard mountable upon the lower sash and overhanging the chain mounting plate for supporting and shielding the chain between the plate and the hook.

TOLBERT HANNON.
